LESTER L. JONES, OF ORADELL, NEW JERSEY

RADIO RECEIVING SYSTEM

Application filed March 6, 1928. Serial No. 259,451.

This invention relates to radio receiving systems and has special reference to the provision of an electron discharge tube radio receiving circuit or system of high power embodying only a single stage of audio amplification.

As is well known, a common type of radio receiving system comprises a multi-stage radio frequency amplifier, a detector and a multi-stage audio frequency amplifier, all arranged in cascade. In this type of radio receiving system the multi-stage radio frequency amplifier is built so as to develop just sufficient radio frequency voltage for the input of the detector tube to saturate a detector tube operating with a grid condenser and a grid leak; and the audio frequency amplifier is built to amplify the rectified or audio voltage produced by the detector to a degree sufficient to operate the translating instrument, such as a loud speaker. In order to obtain a sufficient amount of amplification of the audio output of the detector, it has generally been necessary to use two or more stages of audio frequency amplification.

The use of a number of stages of audio frequency amplification in the audio amplifiers of prior radio receiving systems was necessitated by the low audio power delivered by the detector tube; but such multi-stage audio frequency amplifiers are attended with a number of serious disadvantages. The plurality of audio stages is accompanied by distortion effects which are the geometric product of the distortions due to the several tubes of the audio amplifier; and the last tube or stage of the amplifier is subject to the liability of becoming overloaded in the operation of the system, resulting in the depreciation of the tone quality of the receiving system. The necessity of thus using two or more stages of audio amplification, as compared with the use of a single stage of audio amplification results in an increase, not only in the cost of the receiving system, but also in the cost of equipment which is provided in power operated receivers for filtering out the supply voltage fluctuation, it being necessary to filter out such fluctuations to a high degree in receivers using high audio ampli-

fication. These disadvantages disappear when a single stage of audio amplification is used, but in systems of the prior art the volume produced by a single stage of audio amplification is insufficient for loud speaker operation, this being due to the saturation effect in the detector which prevents it from developing more than a small amount of audio output.

The prime object of my present invention is directed to the provision of a radio receiving system embodying only one stage of audio amplification, with all the advantages consequent thereto, in which the detector is capable of developing an audio output of a magnitude sufficient to be amplified by said single stage of audio amplification for full loud speaker operation.

I have discovered that the detector tube or stage may be given such predetermined constants, and that the radio frequency amplifier may be related to the detector in such a way, as to generate sufficient audio output in the detector to fully load a single stage of amplification such as that provided by a power tube, and thus produce sufficient audio amplification for all normal loud speaker operations. I have further empirically determined that the constants of the audio frequency stage may be so related to those of the detector and radio amplifier stages that the audio tube may be fully loaded by the audio output developed by the detector without causing any overloading of said audio tube over any part of the range of detection operation of said detector stage. The prime object of my present invention centers about the production of radio receiving apparatus in which these discoveries are applied.

To the accomplishment of the foregoing and such other objects as will hereinafter appear, my invention consists in the method and the circuit elements and their relation one to the other, as hereinafter are more particularly described and sought to be defined in the claims, reference being had to the accompanying drawings which show the preferred embodiment of my invention, and in which:

Fig. 1 is a schematic view showing the in- 100

terrelation of the parts of a radio receiving system embodying the invention,

Fig. 2 is a wiring diagrammatic view of the same showing the circuit interrelation between the parts or sections thereof, and

Fig. 3 is a view of a graph explanatory of some of the principles of the invention.

Referring now more in detail to the drawings and having reference first to Figs. 1 and 2 thereof, my invention comprises the arrangement in cascade or series of a radio frequency amplifier generally designated as A embodying a plurality of radio frequency stages, a detector stage B of the vacuum tube type, a single step or stage audio amplifier C embodying a power tube, and an audio translating apparatus such as the loud speaker D of any approved type, the constants of the detector B being so predetermined and the constants of the radio frequency amplifier A and audio frequency amplifier C being so related thereto that the detector is capable of developing a high audio output which may be sufficiently amplified by the single audio stage C to produce full volume operation of the loud speaker D.

I have empirically determined that when the detector tube B is operated by grid bias rather than by a leaky grid condenser, and is furthermore provided with a high biasing grid voltage and with a correspondingly high plate voltage, and that when the detector tube is supplied with a sufficiently high radio frequency input comparable in voltage to the high grid biasing voltage, the detector tube is capable of developing an audio output of a magnitude sufficient to permit its working directly into, and fully loading a power tube audio stage. More specifically, I have found that when the bias on the grid of the detector stage is raised to the order of 10 to 20 volts, with a correspondingly high plate voltage such as 100 to 200 volts, and when the radio frequency amplifier is built to produce a high gain or amplification enough to develop a high radio frequency voltage at the input of the detector, over a range of 1 to 10 volts, the desired high audio output is produced capable of employment with a single power stage related thereto so as to be fully loaded thereby.

In applying these discoveries, I first determine the constants to be imposed upon the detector tube B, which detector tube may comprise a three-element electron discharge device having a filament or cathode f fed by a filament supply A', an input or grid-filament circuit i connected to the output of the R. F. amplifier A and an output circuit o connected to the plate p of the tube, the said output circuit including a primary P of an audio transformer T having the secondary S. These imposed constants include the biasing of the grid g of the detector tube negatively with a voltage of the order of at least 10 to

20 volts, the same being supplied by a battery or other energy source C', and the use of correspondingly high plate potentials derived from a source B'; and as shown in Fig. 2 of the drawings, the negative grid bias may be minus 20 volts, while the applied plate voltage is about 200 volts. Then in order to utilize for the purposes of my invention the long straight line portion of the detection characteristic of a detector having these imposed constants, the input voltage at the input circuit i of the detector is made high enough to produce a grid swing of the order of magnitude of the biasing grid voltage, namely, of the order of 10 to 20 volts. This I accomplish by the use of a high gain radio frequency amplifier A which may, for example, comprise five stages of radio frequency amplification of the untuned type organized and arranged as disclosed and claimed in my copending application, Serial No. 205,934 for radio receiving apparatus, filed July 15, 1927. By means of these constants I am enabled first, to produce a long linear detection characteristic for the detector, as shown in Fig. 3 of the drawings, and then to provide a radio frequency input voltage for the detector of a magnitude sufficient to swing the grid over a voltage sufficient to utilize substantially the full linear portion of said detection characteristic. The detector stage B is thereby enabled to yield an audio output of sufficient power to work directly into the single stage power tube C.

The constants of the single power stage C are then determined so that the high audio output of the detector is amplified to produce full volume operation of the loud speaker D, and preferably so that at the saturation point of the detector stage B the power tube C is just fully loaded, this obviating the possibility of overloading the power tube. To accomplish these results, the power stage which also comprises a three element electron discharge device having the filament or cathode f' , the grid g' and the plate p' , has its grid energized at a fairly high voltage, usually of the order of 50 volts, in order to deliver the full output. In order to generate a commensurate audio frequency voltage on the grid of the power tube, the ratio of the transformer T should be a step-up ratio of approximately 3 to 1, the audio output of the detector tube B having the aforesaid constants supplying approximately 20 volts. With known power tubes having an amplification factor of 3, the 50 volts developed on the grid g' correspond to 150 volts on the plate p' , and therefore to a swing of over 400 volts, which is approximately as high as present day power equipment provides. Therefore, to interrelate the single stage audio amplifier with the preceding parts of the system, I first determine the maximum audio output voltage of the detector and then the maximum load

grid voltage for the audio or power tube, and provide a step-up transformer between the detector and audio tube so that its ratio is the ratio of these two voltages. If the transformer ratio is higher than can be commercially achieved without introducing frequency distortion, then the biasing voltages on the detector should be correspondingly increased. The grid g' of the power tube C 10 is also preferably biased negatively by means of a voltage supply C^2 which may deliver, say, a minus 40 volt bias, and the plate p' of the tube may be provided with voltages of about 200 volts from the battery or other supply B'. 15

In Fig. 3 of the drawings I show graphically a curve representing the detector characteristic produced by biasing the grid in accordance with the principles of my present invention, the same being compared with the detector characteristic of a detector of the prior art, using a grid leak and condenser. In this graph, the R. F. detector input voltages are plotted as abscissæ and the audio 20 detector output voltages are plotted as ordinates, the dotted curve α representing the detection characteristic when the grid is biased negatively with 9 volts, and when a plate voltage of 90 volts is used. The full 25 line curve y is for a grid leak and condenser type of detector with the conventional .00025 mmfd. grid condenser and 2 megohms grid leak, using 45 volts for the plate. By comparison of these two curves it will be seen 30 that the saturation curve of the detector characteristic y is reached when the audio output voltage is below 4 volts, while the saturation of the detection characteristic α resulting from the employment of the principles of my 35 invention is at or about an audio output voltage of 30 volts. These voltages are stepped-up approximately 3 to 1 by the audio transformer T. The relative linearity of the two characteristics α and y can be determined 40 by reference to the straight lines J and K drawn from the origin o through a mean value of the curves α and y , these straight lines representing the ideal detector characteristics with respect to proportionality of 45 output voltage to input voltage. Referring to the biased grid curve α in the region of 27 volts, it will be seen that the characteristic is 13% over the ideal condition, while at 2.7 volts ($\frac{1}{10}$ the value) it is about 54% of the 50 ideal condition. Corresponding values for the grid leak characteristic are 15% over and only 38% at the $\frac{1}{10}$ voltage value. If the comparison be made on the basis of similar fractional parts of the input voltage the 55 grid leak characteristic is about only 10% of the ideal curve at the lower value. This comparison illustrates the greater proportionality of the high grid bias curve α when used over its whole length.

The various advantages resulting from the

invention will now be apparent. The high gain R. F. amplifier supplies a radio frequency input for the detector having a voltage comparable in magnitude with the high grid biasing voltage of the detector, the magnitude being sufficient to swing the grid over a voltage utilizing in the audio output of the detector the full linear portion of the detector characteristic α thereof. The constants of the system are such that the detector approaches saturation just before the power tube is fully loaded, and when the detector saturates and is incapable of giving forth more audio signal the power tube is just fully loaded and therefore cannot be overloaded upon saturation of the detector. A greatly improved tone quality is therefore made possible because of the operation of the detector over a greater portion of its linear characteristic. The receiving set may be made more 35 economically because of the lower cost of the additional radio frequency amplification required by the high gain R. F. amplifier as compared with the cost of additional audio frequency amplification. This cost can be 40 reduced further especially in power operated receivers because of the possible elimination of equipment for filtering out supply voltage fluctuations to the high degree that was previously found necessary with receivers using 45 high audio amplification.

Another important advantage of the system of my invention which further shows the characteristics thereof as compared with the systems of the prior art is the substantial 50 freedom of my system from fading effects. Where the detector voltages are set at values just high enough to fully load the audio tube as the detector saturates, a large increase of radio frequency input into the detector 55 causes no increase in audio volume and produces extremely slight changes in the tone quality of the audio output. Then when the signal increases in intensity due to transmission effects, the loud speaker volume does not change. Similarly, when the transmission is weakened, the loud speaker volume remains constant over a considerable degree of weakening of the signal, because the weakening of the signal merely produces a lesser 60 amount of saturation of the detector. This phenomena produces the equivalent of automatic volume controls which are coming more into use at the present time. In the prior art systems, however, on the contrary, 65 the detector was worked at a region well below saturation. Although the voltage output of the detector was small, it was followed by a sufficient amount of audio amplification to enable this small output to fully load the power tube; then when the signal intensity was increased, the detector would give out 70 more audio output and therefore overload the power tube. The audio system was thus related to the detector stage in the prior art 75

as to be subject to the disadvantages flowing from fading effects.

While I have shown and described my invention in the preferred form, it will be apparent that many changes and modifications may be made in the structure disclosed without departing from the spirit of the invention, defined in the following claims.

I claim:

1. An electron discharge tube radio receiving circuit comprising a multi-tube radio frequency amplifier, a grid biased tube detector, a single stage audio frequency amplifier, and a loud speaker all arranged in cascade, means to impress a high biasing voltage on the grid of the detector tube, a source of high plate voltage therefor, the grid and plate voltages being sufficiently high to give the detector characteristic a linear portion so large that if substantially fully utilized the detector output need only be amplified by the single stage audio frequency amplifier to produce full volume operation of said loud speaker, and the gain in the multi-stage radio frequency amplifier being high enough to provide an input for the detector tube of sufficient magnitude to utilize substantially the full linear portion of the detector characteristic thereof.
2. An electron discharge tube radio receiving circuit comprising a multi-stage radio frequency amplifier, a tube detector, a single stage audio frequency amplifier, and a loud speaker all arranged in cascade, means to impress a biasing voltage on the grid of the detector tube of the order of at least 10 to 20 volts, the gain in the radio frequency amplifier being sufficient to supply an input voltage to the detector comparable in magnitude with the high grid biasing voltage thereof, and a source of commensurately high plate voltage for the detector, whereby the resulting augmented audio frequency output developed by the detector tube is sufficiently amplified by the single stage audio frequency amplifier to produce full volume operation of said loud speaker.

3. An electron discharge tube radio receiving circuit comprising a multi-stage radio frequency amplifier, a tube detector, a single stage audio frequency amplifier, and a loud speaker all arranged in cascade, the circuit constants including a high biasing voltage for the grid of the detector tube, a high gain for the radio frequency amplifier sufficient to supply an input voltage to the detector comparable in magnitude with the high grid biasing voltage thereof, and a high plate voltage for the detector, whereby the resulting augmented audio frequency output developed by the detector is sufficiently amplified by the single stage audio frequency amplifier to produce full volume operation of said loud speaker, and the single stage audio frequency amplifier having constants so related to the

said preceding circuit constants that the audio output developed by the detector is sufficient to substantially fully load the audio frequency amplifier but insufficient to overload the same.

4. An electron discharge tube radio receiving circuit comprising a multi-stage radio frequency amplifier, a tube detector, a single stage audio frequency amplifier, and a loud speaker, means to impress a biasing voltage on the grid of the detector tube of the order of at least 10 to 20 volts, a source of commensurately high plate voltage therefor, the radio frequency amplifier having a gain sufficiently high to provide a radio frequency input for the detector tube of a magnitude sufficient to utilize substantially the full linear portion of the detection characteristic thereof, the single stage audio frequency amplifier comprising a power tube connected by a step-up transformer to the output circuit of the detector tube and so related to said preceding circuits as to permit the power tube to be substantially fully loaded by the audio frequency output of the detector, and further so related to the linear portion of the detection characteristic as to prevent over-loading of said power tube when the entire linear portion of said detection characteristic is utilized.

5. In the operation of a radio receiver including radio and audio frequency amplifiers, a loud speaker, and a detector, the method of avoiding difficulties caused by multi-stage audio frequency amplification and of obtaining the desired loud speaker output volume which includes decreasing the audio frequency amplification to a gain conveniently obtainable in a single stage thereof, commensurately increasing the radio frequency amplification to obtain the desired undiminished audio frequency output volume, and sufficiently raising the saturation point of the detector to accommodate the increased energy supplied thereto.

6. In the operation of a radio receiver including radio and audio frequency amplifiers, a detector tube, and a loud speaker, the method which includes decreasing the audio frequency amplification to a gain conveniently obtainable in a single stage thereof, commensurately increasing the radio frequency amplification to obtain the desired loud speaker volume, obtaining rectification in the detector tube by biasing the grid thereof, and increasing the grid bias and anode potentials applied thereto in order to sufficiently raise the saturation point thereof to accommodate the increased radio frequency energy without distortion.

7. In the operation of a radio receiver including radio and audio frequency amplifiers, a loud speaker, and a detector, the method of avoiding difficulties caused by multi-stage audio frequency amplification

- and of obtaining the desired loud speaker output volume which includes decreasing the audio frequency amplification to a gain conveniently obtainable in a single stage thereof, commensurately increasing the radio frequency amplification to obtain the desired undiminished audio frequency output volume, and raising the saturation point of the detector sufficiently to accommodate the increased energy supplied thereto but insufficiently to overload the audio frequency amplifier. 8. In the operation of a radio receiver including radio and audio frequency amplifiers, a detector tube, and a loud speaker, the method which includes decreasing the audio frequency amplification to a gain conveniently obtainable in a single stage thereof, commensurately increasing the radio frequency amplification to obtain the desired loud speaker volume, obtaining rectification in the detector tube by biasing the grid thereof, and increasing the grid bias and anode potentials applied thereto in order to raise the saturation point thereof sufficiently to accommodate the increased radio frequency energy without distortion, but insufficiently to overload the audio frequency amplifier. 9. In the operation of a radio broadcast receiver having a detector and an audio frequency amplifier including a power tube, the method of preventing the undesirable distortion caused by overloading of said power tube which includes so adjusting the constants of the detector that it will saturate at a value at or below that which is capable of overloading said power tube. 10. A radio receiver comprising a radio frequency amplifier, a detector, an audio frequency amplifier, and a translating device necessitating an audio frequency output volume ordinarily obtained by the use of two or more audio frequency amplifying stages, the audio frequency amplifier consisting of only a single stage, the radio frequency amplifier having a commensurately increased gain in order to obtain the desired audio frequency output volume without diminution, and the detector having a sufficiently high saturation point to accommodate the increased radio frequency energy supplied thereto. 11. A radio receiver comprising a radio frequency amplifier, a detector tube, an audio frequency amplifier, and a loud speaker, the audio frequency amplifier consisting of only a single stage, the gain in the radio frequency amplifier being commensurately increased in order to obtain the desired loud speaker volume, and the detector tube being operated by biasing the grid thereof, a source of a relatively high grid bias potential therefor, a source of relative high anode potential therefor, the grid bias and anode potentials being sufficiently high to raise the saturation point of the detector sufficiently high to accommodate the increased radio frequency energy supplied thereto without distortion, but insufficiently to permit overloading of the audio frequency amplifier. 12. A radio receiver comprising a radio frequency amplifier, a detector, an audio frequency amplifier, and a translating device necessitating an audio frequency output volume ordinarily obtained by the use of two or more audio frequency amplifying stages, the audio frequency amplifier consisting of only a single stage, the radio frequency amplifier having a commensurately increased gain in order to obtain the desired audio frequency output volume without diminution, and the detector having a saturation point sufficiently high to accommodate the increased radio frequency energy, but insufficiently high to permit overloading of the audio frequency amplifier. 13. A radio receiver comprising a radio frequency amplifier, a detector tube, an audio frequency amplifier, and a loud speaker, the audio frequency amplifier consisting of only a single stage, the gain in the radio frequency amplifier being commensurately increased in order to obtain the desired loud speaker volume, and the detector tube being operated by biasing the grid thereof, a source of a relatively high grid bias potential therefor, a source of relatively high anode potential therefor, the grid bias and anode potentials being sufficiently high to raise the saturation point of the detector sufficiently high to accommodate the increased radio frequency energy supplied thereto without distortion, but insufficiently to permit the detector output to overload the audio frequency amplifier. 14. A radio broadcast receiver comprising a detector and an audio frequency amplifier including a power tube coupled thereto, the constants of the detector being so adjusted as to saturate at an energy value at or below that which is capable of overloading the power tube, in order to prevent overloading and undesirable distortion in said power tube.
